UNITED STATES PATENT OFFICE.

LEVI H. MONTROSS, OF CAMDEN, NEW JERSEY, ASSIGNOR TO INTERNATIONAL MATCH COMPANY, A CORPORATION OF PENNSYLVANIA.

MATCH-MAKING MACHINE.

SPECIFICATION forming part of Letters Patent No. 790,306, dated May 23, 1905.

Application filed February 11, 1901. Serial No. 46,860.

To all whom it may concern:

Be it known that I, LEVI H. MONTROSS, of the city of Camden, county of Camden, and State of New Jersey, have invented an Improvement in Match-Making Machines, of which the following is a specification.

My invention relates to match-making machines; and it consists of certain improvements, which are fully set forth in the following specification and are shown in the accompanying drawings.

A part of my improvements relates to a continuously-operating or automatic machine—*i. e.*, one in which the splints are cut and introduced into an endless traveling carrier, headed, dried, and ejected as finished matches without intermediate handling. As the splint cutting and introducing operations are intermittent, it is usual to suspend or interrupt the forward travel of the carrier while the splints are introduced, and this results in an interrupted movement of other portions of the carrier.

It is one of the objects of my invention to accomplish this suspension or interrupting of the forward travel of the carrier while the splints are being introduced without suspending or interrupting the continuous forward travel of the carrier at those portions where the match heading or ejecting operations are taking place. This result I accomplish by devices which convert the forward travel of the carrier into a reciprocating motion in the line of movement of the splint-introducing devices, so that no forward motion of the carrier with reference to the splint-introducing devices takes place during the introduction of the splints and at the same time the regular continuous travel of the other portions of the carrier is not interrupted.

My invention also embraces minor combinations of mechanisms and novel constructions, which are fully set forth in the claims.

In the drawings, Figure 1 is a side elevation of a portion of a match-making machine with part in longitudinal vertical section, only so much of the machine being shown as is necessary to explain my invention. Fig. 2 is a longitudinal vertical sectional view of a part

of the same, showing the splint cutting and introducing devices in a position different from that shown in Fig. 1. Fig. 3 is a transverse vertical sectional view of the splint cutting and introducing devices, taken on the line A A of Fig. 1. Fig. 4 is a front elevation of the composition-applying devices, and Fig. 5 is a perspective view of a portion of the splint-carrier.

a is a traveling splint receiver and carrier made up of a series of parallel transverse bars or portions, between which the splints are introduced and carried during the heading and drying operations and from which they are finally ejected by the ejecting devices. So far as the other features of my invention are concerned the particular construction of this carrier is not material. The construction shown consists of two chains of links *a'* *a'*, carrying transverse bars *b*, each pair of opposite links being adapted to carry a series of bars, (three are shown,) the bars being provided on their ends with trunnions *b'*, inserted in sockets *a*² in the links and held against rotation (which would result in the displacement of the splints) by flattened end faces *b*², received in longitudinal grooves *a*³ on the inner faces of the links. If desired, each link may carry two bars or more than three, or any of the other forms of splint receiving and carrying devices may be used. The bars may be grooved or roughened, if desired, to render their hold upon the splints more firm; but this is not necessary.

In practice the carrier *a* is usually continuous and extends through the splint cutting and receiving devices, where it receives the splints, thence through the heading devices, where the heads are applied, then through the air or through driers for a greater or less extent (not shown) for the purpose of drying the heads, and finally to the ejecting devices by which the finished splints are expelled. From the ejecting devices the carrier returns again to the splint cutting and receiving devices to receive new splints, and the operation of heading, drying, and expelling is repeated. The carrier passes over suitable guides and is driven in its movements by sprocket-wheels,

which in practice may be located at different portions of the machine and to which power may be transmitted in any convenient way. I have shown only so much of these driving devices as is necessary to an understanding of my invention.

I shall separately describe the splint cutting and introducing devices, the match-heading devices, and ejecting devices.

- 10 *The splint cutting and introducing devices.*—
 cccc are carrier guiding and feeding sprocket-wheels by which the carrier is fed through the splint cutting and receiving devices. They are shown carried by transverse shafts c' c',
 15 journaled in side frames d d, and engage the spaces between the bars of the belt adjacent to the outer ends thereof. These sprocket-wheels are driven by bevel-gears d' d' from a longitudinal shaft d², operated by worm-gear-
 20 ing d³ from a vertical shaft d⁴, driven by bevel-gears from the main driving-shaft e. (See Fig. 3 and dotted lines in Fig. 1.)

f f are vertically-movable guides or wheels, under which the carrier a passes, located between the sprocket-wheels c c. As shown, these disks are carried by a transverse shaft f', journaled in frames f² f², guided in vertical guides f³ in the side frames d d and normally held in an elevated position by springs f⁴ f⁴,
 30 which are shown connected with the frames f² f² by yokes f⁵ f⁵.

g g and g' g' are pairs of auxiliary guide wheels or disks carried by the frames f² f², one pair on each side of the disks f f, over
 35 which the carrier passes, as shown in Fig. 1. These guide-disks are arranged close to the wheels f f, so that the carrier will be bent about the periphery of the wheel f f, as shown, and the pair of guide-disks, as g' g', on one
 40 side are arranged at a higher elevation than the disks g g on the other side, the arrangement being such that with the frames f² f² elevated, as in Fig. 1, the section of the carrier lying between the disks g g and the in-
 45 feeding-sprockets c will lie substantially horizontal, while the section on the other side between the disks g' g' and the outfeeding-sprockets will incline upwardly. This is clearly shown in Fig. 1.

50 h h are cams carried by a shaft h', journaled in the side frames d d and acting through pivoted dogs h² h² on the frames f² f² to depress the frames and the guide-wheels carried thereby at intervals. The cam-shaft h' may be
 55 driven by any suitable driving connections, as by bevel-gears h³, from the vertical shaft d⁴.

i is a reciprocating cutter-frame carrying the cutters i', which act upon the block i² in the usual manner to cut a series of splints
 60 c from the edge thereof on the descending movement and lift the splints to the carrier on the ascending movement. As the construction of these cutting devices and the means for feeding the block are thoroughly understood, I
 65 have not undertaken to show them more in

detail than is necessary to render my invention intelligible.

Any suitable splint-cutting devices may be employed by which the splints are cut from the edge of the block by vertically-reciprocating cutters. I have shown the cutter-frame i driven from a crank i³ of the power-shaft e through a rod i⁴.
 70

The operation of the splint-cutter is so timed with reference to the movement of the carrier that it reaches its highest position to insert the splints between the bars at the moment the carrier is depressed by the guides f f. The forward movement of the body of the carrier is continuous throughout the machine; but by 75 the peculiar arrangement and movement of the guides f f, g g, and g' g' the forward travel of that portion of the carrier which receives the splints from the cutters is suspended while the splints are being introduced, and 80 this suspension of the forward movement is effected without interrupting the continuous forward movement of the other portions of the carrier. With the carrier in the position shown in Fig. 1 when the guides f f, g g, 85 and g' g' are elevated the carrier-section between g and c is horizontal, while that between g' and c is inclined. At this moment the cutters are just reaching their highest position to 90 introduce the splints. The cams h then with a quick movement depress the frames f² f² and the guides f f, g g, and g' g', the effect 95 of which is to make the section c to g inclined (and consequently longer) and the section c to g' straight, (and consequently shorter,) 100 as shown in Fig. 2. This lengthening of the section c to g takes up the extent of its forward movement without producing any forward movement in the section between the guides g g and g' g', and the shortening of the section 105 c to g' enables the sprocket c to take up the extent of the forward movement on the other side, also without affecting the section between g and g'. The return of the guides f f, g g, g' g' to the positions shown in Fig. 1 moves the section between g and g' forward the distance of 110 one bar without producing any forward movement in the carrier beyond the sprockets c c c c. Thus the forward movement of that section of the carrier in which the splints are introduced is suspended at the moment of receiving the splints without interrupting the continuous motion of the other part of the belt.
 115

Means must be employed for closing the 120 backs of the cutters and forcing the splints into the carrier. For this purpose I employ a movable striker or back-stop, which at the moment the cutters are about to introduce the splints into the carrier strikes the cutter-eyes 125 and forces the splint out of them and into the carrier. As shown, this striker consists of a transverse bar j, preferably of hard wood, carried by arms j² on a rock-shaft j', journaled transversely in the side frames d d and above 130

the wood feeder. When the striker is at rest, as shown in Fig. 1, it is just out of the path of the cutters, so as not to interfere with their movements. When the cutters have ascended 5 to the position shown in Fig. 1 and are on the point of introducing the splints into the carrier, the striker is thrown up and strikes the cutter-eyes, forcing the splints into the carrier. Any suitable mechanism may be employed 10 for operating the striker. I have shown a bar j^3 carried by the cutter-frame and operatively connected with the rock-shaft by means of teeth j^4 , engaging teeth or lugs j^5 on the rock-shaft. The construction should 15 be one which will impart a quick upward movement to the striker and enable it to return out of the path of the cutters before they descend. I prefer to form the operative face of the striker with projections which will enter the eyes of the cutters, and thus act as hammers to drive out the splints into the carrier. By using a wooden bar j these projections will be formed in the wood by the action 20 of the striker, and their proper location will be insured. There will also be less danger of injury to the cutting edges of the eyes.

The match heading and ejecting devices.—The carrier thus provided with rows of splints passes with a continuous motion through the 25 heading devices. I have shown the carrier passing on guides k , by which the heads of the splints are carried through the usual paraffining-pan k' and thence over guides k^2 to the guide or drum k^3 above the composition-applying drum l , which is journaled in the 30 composition-pot l' , so as to be partly submerged therein. The carrier-guide k^3 may be driven in any suitable manner—*e. g.*, by the sprocket-chain k^4 from the power-shaft e . Carried by the shaft of the guide k^3 is a friction-wheel m , the diameter of which is approximately equal to the diameter of the guide k^3 and carrier plus the projecting length of the splints. Carried by the shaft of the composition-drum is a friction-wheel m' , of a diameter approximately equal to that of the composition-drum, which runs in frictional contact with the wheel m of the guide k^3 and is driven by friction thereby. By facing the 45 wheels m and m' with rubber or other flexible material a yielding driving connection is afforded which will reduce the scraping of the splint-heads on the drum-surface.

The composition-pot is usually provided 50 with a steam-chest l^2 to keep the composition heated.

It is desirable that the composition should be kept stirred or agitated, and for this purpose I provide an agitating device which is 55 kept moving through the composition. This agitating device consists of a bar n , extending adjacent to the surface of the drum within the pot and carried by rocking arms $n' n'$ on the drum-journal, one of said arms being provided with an extension n^2 , which receives a

reciprocating rod n^3 , operated by a crank n^4 on a shaft n^5 , operated by a guide or sprocket n^6 , driven by the carrier or by independent driving devices. By these means the bar n is rocked back and forth in the composition 70 to keep it stirred up. The rod n^3 is preferably detachably connected with the agitating device, and I have shown it connected with the extension n^2 by a jaw.

Owing to the liability of fires from the ignition of the matches in the carrier it is desirable that means should be provided for removing the composition-pot from its position adjacent to the match-carrier. For this purpose I have shown the composition-pot l' 75 mounted on wheels o on a track p , the body of the track being substantially below the carrier, but provided with an elevated section or portion p' , which will elevate the pot when drawn upon it to bring the surface of 80 the composition-drum in position to act upon the splints, as shown in Fig. 1. The pot may be secured in this position by any convenient device, such as the screw r , and may be adjusted by the adjusting-nut r' . To remove 85 the composition-pot, it is only necessary to detach the rod n^3 and release the pot, when it will descend by gravity on the track $p p'$ away from the carrier a .

Any convenient form of match-ejecting devices may be employed. I have shown a drum s , provided with a series of longitudinal ribs s' , adapted to enter the spaces in the carrier from the rear as the carrier travels over it and eject them upon an apron or receiver 90 t . The ejecting-drum is driven continuously with the carrier, either by the carrier itself or by suitable driving connections. Thus the operations of heading the splints and ejecting the matches are continuous or uninterrupted, 95 while the splint cutting and introducing devices operate intermittently, this being effected by the reciprocating guides $f f', g g', g' g'$, which suspend the forward travel of the carrier while the splints are being introduced 100 without affecting the continuous forward travel of the body of the carrier.

I do not mean to limit my invention to the details of construction which have been shown, as they may be varied without departing from 105 my invention.

What I claim as new, and desire to secure by Letters Patent, is as follows:

1. In a match-making machine, the combination of a splint-carrier, means to introduce 110 the splints into the carrier, driving devices for imparting a continuous traveling motion to the carrier, guides for guiding the carrier while it receives the splints, and means for moving said guides to take up the forward 115 movement of the carrier during the introduction of the splints, whereby the forward movement of the carrier with reference to the splint-introducing devices is suspended 120 during the introduction of the splints without in- 125 130

terrupting the continuous traveling motion of the body of the carrier.

2. In a match-making machine, the combination of a splint-carrier, reciprocating splint-introducing devices adapted to introduce the splints into the carrier, driving devices for imparting a continuous traveling motion to the carrier, and means acting on the carrier to move it in the line of movement of the splint-introducing devices at the moment of introducing the splints, whereby the forward travel of the carrier with respect to the splint-introducing device is suspended at the moment of introducing the splints without interrupting the continuous forward travel of the body of the carrier.

3. In a match-making machine, the combination of a splint-carrier, reciprocating splint-introducing devices adapted to introduce the splints into the carrier, driving devices for imparting a continuous traveling motion to said carrier, guides for said traveling carrier located on each side of the point at which the splints are introduced, movable guides for said carrier between the first-mentioned guides and the point at which the splints are introduced, said movable guides being arranged in different horizontal planes, and means to reciprocate said movable guides in the direction of the reciprocation of the splint-introducing devices at the moment the splints are being introduced, whereby the forward traveling motion of the carrier is suspended at the moment the splints are introduced without interrupting the continuous forward travel of the body of the carrier.

4. In a match-making machine, the combination of a splint-carrier, reciprocating splint-introducing devices adapted to introduce the splints into the carrier, driving devices for imparting a continuous traveling motion to said carrier, guides for said traveling carrier located on each side of the point at which the splints are introduced, movable guides for said carrier between the first-mentioned guides and the point at which the splints are introduced, said movable guides being arranged in different horizontal planes, guides for said car-

rier located between said movable guides and moving with them, and means to reciprocate said movable guides in the direction of the reciprocation of the splint-introducing devices at the moment the splints are being introduced, whereby the forward traveling motion of the carrier is suspended at the moment the splints are introduced without interrupting the continuous forward travel of the body of the carrier.

5. In a match-making machine, the combination of a splint-carrier, reciprocating splint-introducing devices adapted to introduce the splints into the carrier, driving devices for imparting a continuous traveling motion to said carrier, guides *c, c, c, c*, located on each side of the point at which the splints are introduced, movable guides *f, f* located between the guides *c, c, c, c*, guides *g, g* and *g', g'*, *g'* movable with the guides *f, f* and located one pair on each side thereof and in different horizontal planes with reference to the guides *c, c, c, c*, and means to reciprocate said guides *f, f, g, g, g', g'*, in the line of reciprocation of the splint-introducing devices at the moment the splints are being introduced.

6. In a match-making machine, the combination of a splint-carrier, reciprocating splint-introducing devices adapted to introduce the splints into the carrier, driving-guides *c, c, c, c*, located on each side of the point at which the splints are introduced and imparting a continuous forward traveling motion to said carrier, movable guides *f, f* located between the guides *c, c, c, c*, guides *g, g* and *g', g'*, *g'* movable with the guides *f, f* and located one pair on each side thereof and in different horizontal planes with reference to the guides *c, c, c, c*, and means to reciprocate said guides *f, f, g, g, g', g'* in the line of reciprocation of the splint-introducing devices at the moment the splints are being introduced.

In testimony of which invention I have hereunto set my hand.
